AUTOMATIC FIREARM

Marriner A. Browning, Ogden, Utah, assignor to
 J. M. & M. S. Browning Company, Ogden,
 Utah, a corporation of Utah

Application April 10, 1934, Serial No. 719,862

13 Claims. (Cl. 89—2)

The general object of the present invention is to provide an automatic firearm or machine gun which is simple in construction, reliable in operation, of light weight and capable of sustained 5 operation without excessive heating. As to its more important phases the invention is particularly applicable to a gun of the gas operated type, the barrel being normally rigidly connected with the breach casing.

10 In accordance with the invention the cartridge feed channel is below the barrel and the cartridges are fed by means of a slide positioned below the feed channel and operated by the gas actuated operating slide. The operating slide and 15 also the cartridge feed slide are preferably removable.

Further in accordance with the invention I provide an improved means for transferring the cartridges from the feed channel to the chamber 20 of the barrel.

25 In the accompanying drawings I have shown one embodiment of the invention, but it will be understood that the drawings are for illustrative purposes only and are not to be relied upon as limiting or defining the scope of the invention, the claims forming a part of this specification being relied upon for that purpose.

Of the drawings:

Fig. 1 is a side view of a firearm embodying the 30 invention.

Fig. 2 is an enlarged fragmentary view of the rear portion of the firearm, this view being partly a side view and partly a longitudinal sectional view.

35 Fig. 3 is a view similar to Fig. 2, but showing the parts in different relative positions.

Fig. 4 is an enlarged fragmentary view of the front portion of the firearm, this view being partly a side view and partly a longitudinal sectional view:

40 Fig. 5 is a view similar to Fig. 4, but showing the parts in different relative positions.

Fig. 6 is a fragmentary perspective view of the rear portion of the barrel.

45 Fig. 7 is a transverse sectional view taken along the line 7—7 of Fig. 4.

Fig. 8 is a transverse sectional view taken along the line 8—8 of Fig. 3.

50 Fig. 9 is a perspective view showing the extractor.

Fig. 10 is an enlarged fragmentary horizontal sectional view taken along the line 10—10 of Fig. 1.

55 Fig. 11 is a view similar to Fig. 10, but showing the parts in different relative positions.

Fig. 12 is a plan view of the operating slide, together with a part of the piston rod.

Fig. 13 is a side view of the parts shown in Fig. 12, this view being partly in section along the line 13—13 of Fig. 12.

5

Fig. 14 is a perspective view of the feed slide.

Fig. 15 is a transverse sectional view taken along the line 15—15 of Fig. 11.

Fig. 16 is a view taken along the line 16—16 of Fig. 10 and showing in detail the extractor and 10 the cam mechanism which operates it. In this view the extractor, the pressure lever for the extractor and the cam mechanism are shown in full lines and all other parts are shown in dot-and-dash lines.

15

Figs. 17, 18 and 19 are views similar to Fig. 16, but showing the parts in different relative positions.

20

Figs. 20 and 21 are fragmentary views similar to portions of Figs. 2 and 3, but showing the retarding mechanism parts in different relative positions.

25

Fig. 22 is an enlarged fragmentary plan view taken along the line 22—22 of Fig. 21.

30

Fig. 23 is an enlarged fragmentary longitudinal sectional view taken along the line 23—23 of Fig. 22.

35

Fig. 24 is a view similar to Fig. 23, but showing the parts in different relative positions.

40

Referring to the drawings, 1 represents as an entirety the main breech casing which is generally rectangular in section as shown in Fig. 8. As shown the casing is formed from a single piece of steel although I do not necessarily limit myself to this integral construction. The portion 1^a of the casing is formed to receive the rear end of a barrel 2. Behind the portion 1^a are two main side walls 1^b, 1^b connected near the center by an integral cross member 1^c. An opening 1^d is provided at the front of the cross member 1^c, which opening is normally closed by a pivoted cover 3 held by a releasable latch 3^a. An opening is provided at the rear of the cross member, which opening is closed by a plate 4. The bottom of the casing is normally closed by separate plates 5 and 6. The rear of the casing is normally closed by a plate 7 flanged at its sides and having ribs (not shown) adapted to enter grooves 7^a, 7^a (see Fig. 10) formed in the side walls 1^b, 1^b. A suitable latch 7^b serves to normally hold the end plate 7 in place. Carried by the plate 7 at opposite sides thereof are two brackets 8, 8 carrying handles 9, 9.

45

The barrel 2 is preferably detachably connected with the casing and has a rear cylindrical por-

50

55

tion 2^a which fits a cylindrical hole in the portion 1^a of the casing. The rear end of the barrel is provided at 10 with interrupted external threads adapted to engage similar internal threads formed in the casing. When the barrel is in the position shown in Figs. 2 and 3 it is firmly held in place by the threads. It can be released by being turned through a quarter turn in the clockwise direction as viewed in Fig. 6. 5

10 The barrel is normally held in its locked position by means of a pin 11 held by a spring 12. The rear end of the spring is T-shaped and fits a T-shaped groove 13 in the top of the casing, and a screw 14 normally serves to prevent the spring 15 from moving rearward out of the T-shaped slot. The pin 11 can be withdrawn from the hole in the barrel by means of a suitable tool such as the head of a cartridge and then the barrel can be turned in the clockwise direction to disengage 20 the interrupted threads at 10. This permits the barrel to be drawn out in the forward direction. In order to avoid the necessity for using a tool to replace the barrel, the barrel is provided as shown in Figs. 6 and 15 with a longitudinal 25 groove 15 positioned to receive and provide clearance for the pin 11. The groove 15 has a beveled surface 15^a adjacent its forward end, which surface serves to cam the pin 11 outward when the barrel is moved in the counter-clockwise direction into locking position. As soon as locking 30 position is reached the pin 11 snaps into the hole in the barrel, thus firmly locking it.

The barrel 2 may be provided with a series of 35 annular ribs to facilitate cooling, but such ribs are not shown. As already explained the barrel is readily removable, and if excessive heating eventually occurs the gun may be kept in service by removing one barrel and substituting another.

40 The casing 1 is provided with an integral extension 1^e which extends forward underneath the barrel. This extension is hollow and it serves to engage and retain a piston tube 16. The tube 16 is preferably slidable longitudinally with respect to the casing, and its movement is guided in part by a removable pin 17 in the casing extending through a longitudinal slot in the rearward extending portion 16^a of the tube. In addition there is preferably a lip 16^b on the tube extension 45 slidably engaging the wall of a recess 18 in the plate 6. At its forward end the tube 16 is connected with and supported by the barrel. Preferably the tube is provided at the top thereof with a projection 19 having a T-slot therein 50 which fits a T-shaped projection on the barrel. With the parts engaged as shown in Figs. 4 and 7, the tube is held in rigid relationship to the barrel, but by moving the tube rearward it is disengaged from the barrel as shown in Fig. 5, thus leaving the barrel free to be turned so that it 55 may be disengaged from the casing in the manner already explained.

The tube 16 is normally held in its forward 60 engaged position by means of two links 21 and 22 which are pivotally connected with each other by a pin 23. Preferably the link 21 is U-shaped in cross section so as to partly surround and enclose the link 22. The link 21 is pivoted to the front end of the portion 1^e of the casing by 65 means of a removable pin 24, and the link 22 is pivoted to the tube 16 by means of a pin 25. A spring pressed latch 26 is provided for holding the link 21 in its upper or normal position. It will be observed that with the parts in the positions 70 shown in Fig. 4 the tube 16 is held in its forward 75

position, the link 21 substantially enclosing the link 22. When it is desired to move the tube 16 in the rearward direction the link 21 is disengaged from the latch 26 and the link is moved downward to the position shown in Fig. 5, thus drawing the tube rearward and disengaging the projection 19 from the T-shaped projection on the barrel. 5

Longitudinally movable along the bottom of the main casing is an operating slide 27, this slide 10 being connected with a piston rod 28 and a piston 29 positioned within the piston tube 16. As shown the piston rod is connected with the slide by means of a pin 30. Preferably the piston 29 is formed integrally with the rod and consists 15 of one or more annular flanges thereon. A cylinder 31 is provided in the forward end of the tube 16, being held in place by threads, and the piston 29 accurately fits the said cylinder. A series of registering gas holes connect the bore of 20 the barrel 2 with the interior of the cylinder 31 in order that a portion of the gases of explosion may enter the cylinder and act upon the piston 29 to force it rearward.

25 For returning the slide in the forward direction after having been moved rearward by the piston and piston rod, there is provided an action spring 32 supported upon and guided by a rod 33. Preferably the spring 32 and rod 33 extend into a hollow buffer 34 carried by the rear plate 30 7. The spring at its rear end abuts against a head 35 detachably secured in place in the buffer. The spring at its forward end extends into an aperture in the slide 27 and abuts against a shoulder 36. A hole 36^a provides clearance for 35 the rod 33 when the slide is in its rear position.

The slide 27 serves to operate the feeding, loading and firing mechanisms of the gun and these mechanisms will now be described in detail.

Extending transversely through the casing be- 40 low the rear portion of the barrel is a cartridge feed channel 37 adapted for the reception of a cartridge belt, such as A. The channel 37 is sufficiently wide at the left hand side of the gun to permit the entry of cartridges, but preferably 45 its width is only slightly greater than the length of the cartridges. At the right hand side the feed channel is much narrower, being only wide enough to permit the exit of the canvas belt which carries the cartridges. The before-men- 50 tioned plate 6 is formed with upward extensions 6^a, 6^b which have guide openings therein to receive and guide the slide 27. The said plate 6 is also provided with grooves 38, 38 for guiding a transversely and rectilinearly movable feed 55 slide 39. The side walls of the breech casing have apertures therein cooperating with the grooves 38 to form an unobstructed feed slide guide channel. The feed slide with its appurte- 60 nances is in some respects similar to that disclosed in Patent No. 1,293,021 to John M. Brown- 65 ing.

The longitudinally movable operating slide and the transversely movable feed slide have cooperating elements which enable the former to operate the latter. Preferably, these cooperating elements comprise a cam path on one slide and a cooperating cam follower on the other slide.

While the details of arrangement may be varied I prefer to locate the feed slide 39 below 70 the operating slide 27. At the bottom of the slide 27 there is provided a cam path which is preferably in the form of a cam groove 40 cut in the bottom surface of the slide. At least a portion of this groove 40 is inclined with re- 75

spect to the longitudinal movement of the slide, and as shown the cam path also has a longitudinal rear portion 40^a and a longitudinal forward portion 40^b. On the top of the feed slide 39 there is provided means such as a pin 41 for engaging the cam path or groove 40. The feed slide should be made as light in weight as strength requirements will permit, the object of this being to keep the total mass of the moving parts actuated by the operating slide as small as possible so as to obtain maximum speed of operation and to reduce the total weight of the firearm. By forming the cam groove 40 in the operating slide and providing the feed slide 39 with the pin 41 the width of the feed slide can be reduced to that necessary for proper feeding of the cartridges. As shown, the feed slide is substantially less in width than the cartridge feed channel 37. When the slide 27 is in its rear-most position as shown in Fig. 10 the feed slide 39 is at the left hand limit of its movement; and when the operating slide 27 is in its forward position as shown in Fig. 11 the feed slide is at the right hand limit of its movement. Thus longitudinal movement of the operating slide 27 serves to cause transverse movement of the feed slide 39. Carried by the feed slide 39 is a pivoted pawl 42 which is adapted to engage the successive cartridges of the belt A to feed the said belt from left to right during the movement of the feed slide from left to right. The pawl 42 is provided with a tail piece 42^a which underlies and helps to support the cartridge which is engaged. During movement from right to left the pawl 42 passes under the next following cartridge and then snaps upward in position to engage it. A pawl 43 carried by the casing serves to prevent outward movement of the feed belt.

Preferably the slide 27 and the parts associated therewith are removable from the firearm at the rear thereof. To effect such removal it is necessary first to remove the spring 32 and the rod 33 and to then remove the end plate 7 with the parts carried thereby. The slide is then substantially free to be withdrawn in the rearward direction except for the fact that the pin 41 is engaged in the cam groove 40. In order to permit the rearward removal of the cam slide, provision is made to permit the cam engaging means on the feed slide, that is, the pin 41, to be disengaged from the cam path, that is, from the groove 40. This disengagement may be effected in different ways, but I have shown the groove 40 as having a transversely unobstructed portion or opening 44. During the normal reciprocation of the slide 27 the unobstructed portion or opening 44 does not come into register with the pin 41, but by moving the slide rearward slightly beyond its normal limit of movement the opening 44 is brought into register with the pin 41, thus permitting the pin and slide to be moved transversely sufficiently to be disengaged from the cam groove 40. With the pin 41 thus disengaged from the cam groove the slide can be readily withdrawn rearward.

Preferably the feed slide 39 is entirely removable from the firearm, being normally held in place solely by reason of the engagement of the pin 41 with the groove 40. So long as the operating slide 27 remains within its normal range of movement the feed slide 39 is held and removal thereof is prevented. However, when the operating slide is moved sufficiently to bring the opening 44 into register with the pin 41 the feed slide can then be entirely removed from the fire-

arm. In order to prevent the slide 39 from coming out accidentally or when not so desired during removal of the slide 27, there is preferably provided a spring 39^a secured to the bottom of the slide. This spring will engage with the shoulder at 6^b, and will thus resist outward movement of the slide. However, by applying a slight pressure the resistance of the spring can be overcome and the slide can be removed.

The firearm is provided with a reciprocating breech bolt 45 which is guided between the side walls 1^b, 1^b of the casing. The breech bolt is operated and controlled by mechanism operated by the slide 27, this mechanism being similar to that disclosed in Patent No. 1,293,022 to John M. Browning. As shown in Fig. 3 the breech bolt 45 is connected with the slide 27 by means of two links 46 and 47 pivotally connected with each other at 48. The link 46 is pivotally connected with the breech bolt at 49 and the link 47 is pivotally connected with the slide at 50. When the slide 27 is in its rear position as shown in Fig. 3, the two links 46 and 47 are held substantially in alinement in the relative positions shown. A lug 47^a on the link 47 engages the link 46 to prevent downward movement beyond the position shown.

When the slide 27 moves forward under the influence of the action spring 32 the two links 46 and 47 and the breech bolt 45 move in unison with it until the breech bolt nearly reaches its forward position, the link 46 being then approximately in register with the opening 1^d in the top wall of the casing. At or about the time that the link comes into register with the opening the curved portion 46^b of the link 46 engages two cams 51 projecting inward from the respective side walls 1^b, 1^b of the casing. In the drawings only the cam on the left hand side is clearly shown, but it will be understood that there is a similar cam on the right hand side. These cams 51 cooperate with the curved portion 46^b of the link 46 to force the link upward into the opening 1^d, the rear end portion of the link abutting against the rear wall of the opening as clearly shown in Fig. 2. In the meantime the slide 27 has continued its forward movement, thus bringing the link 47 into a substantially upright position. With the parts in the position shown and described, the breech bolt is firmly locked in its forward or breeched position and is well adapted to resist the recoil action incident to firing. Following firing the slide 27 is moved rearward by the action of the gases of explosion in the manner already described, the link 47 serving first to draw the link 46 downward out of locking position and then to move the link 46 and also the bolt 45 rearward to the positions shown in Fig. 3.

Reference has already been made to the fact that the slide 27 can be removed through the rear of the casing. It will be understood that the breech bolt 45 and the links 46 and 47 are similarly removable, all of these parts being removable as a unit.

A firearm incorporating the present invention is intended to be used with cartridges having annular grooves in the heads thereof, and the front end of the breech bolt is provided with vertical ribs 52, 53 which cooperate to form a vertical groove for receiving and retaining the heads of the cartridges. When the breech bolt is in its forward position as shown in Fig. 2 the head of the cartridge which is in central position in the feed channel 37 is vertically below the groove in the front of the breech bolt. For withdrawing the cartridge from the feed channel and lifting

it into proper relationship to the breech bolt there is provided an extractor 54 shown in detail in Fig. 9. This extractor is provided with a pivot pin 55 which fits a transverse pivot opening in the 5 breech bolt, the extractor thus moving bodily rearward and forward as the breech bolt moves. The extractor 54 is provided with a transversely extending tooth 56 which is so shaped and positioned as to enter the groove in the cartridge 10 when the breech bolt and the extractor are in their forward positions as shown in Fig. 2. For pressing the forward end of the extractor upward so as to hold the tooth 56 in firm engagement with the cartridge, there is provided a pressure 15 lever 57 pivoted to the breech bolt at 58 and engaging at its forward end with the extractor. A coil spring 59 tends to move the pressure lever 57 in the counter-clockwise direction, thus pressing the forward end of the extractor upward.

20 A suitable cam mechanism is provided for controlling and guiding the relative movements of the extractor and preferably this mechanism is located at the left side of the firearm. For convenience of construction the left side wall 1^b is 25 cut away to provide an opening 60 as shown in Fig. 3 and this opening is covered by a plate 61, shown in Figs. 10 and 11. The cam mechanism to be now described is carried by the plate 61 and projects inward through the opening 60.

30 The extractor 54 is provided with a pin 62 which projects toward the left and which serves as a means for controlling the upward and downward movements of the extractor. When the breech bolt moves rearward from the position shown in 35 Fig. 2 the extractor 54 withdraws the cartridge with which it is engaged and the extractor is moved upward by the lever 57. Thereafter as shown in Fig. 16 the pin 62 engages a cam surface 63 on the plate 61 which forces the pin upward 40 and thus causes continued upward movement of the extractor. Thus the cartridge is moved not only rearward but also upward. Continued rearward movement brings the parts into the relative positions shown in Fig. 3, the pin 62 being retained between two cam walls.

45 The cam plate 61 carries a pivoted cam member 64 which is normally spring pressed to the position shown in Figs. 3, 17 and 19. However, the pin 62 in moving rearward passes under the 50 rear portion of the cam member 64 and lifts it as shown in Fig. 16. When the parts move forward from the position shown in Fig. 3, the pin 62 moves along the top of the cam member 64 as shown in Fig. 17, thus further lifting the cartridge so that it is brought into exact alignment with the chamber in the barrel. As forward movement continues the cartridge is pushed into the chamber in the barrel as shown in Figs. 18 and 2.

55 60 When the cartridge has been sufficiently entered in the chamber to be retained thereby, the extractor 54 is withdrawn from it, the pin 62 engaging the cam surface 65 as shown in Fig. 18 and being pushed downward. As forward movement continues to the position shown in Fig. 19, the extractor is moved still further downward, the pin 62 being disengaged from the cam members and the extractor being held directly by the cam surface 68. As the extractor reaches the 65 position shown in Fig. 2, the tooth 56 engages the next cartridge and the parts are in positions for a repetition of the loading operation which has just been described.

70 75 As shown in Fig. 8 a second extractor 69 is provided immediately above the cartridge shell

retaining rib 53. This extractor 69 is so shaped and positioned that it is entered in the groove in the cartridge shell when the cartridge is in firing position. The extractor 69 is resiliently mounted, being carried by a spring 70, as shown 5 in Fig. 2. The rear portion of the barrel is provided with a notch 71 into which the extractor 69 projects when in its forward position. With the parts in the position shown in Fig. 2 firing is automatically effected by means to be presently 10 described, and the parts again move in the rearward direction. The shell of the cartridge which has just been fired is held by the extractor 69 and is thus drawn rearward as the bolt moves rearward.

15 Mounted in a groove in the bolt 45 at the left side thereof is an ejector 72, normally held by a spring 73 in its rearward position with respect to the bolt, as shown in Fig. 11. The ejector 72 is connected to the bolt by means of a stud on 20 the bolt extending through a slot in the ejector.

Carried by the casing at the left side thereof is a pin 74 which is in position to engage a shoulder 72^a on the ejector. Just before the breech bolt reaches its extreme rearward position 25 the pin 74 engages the shoulder 72^a and moves the ejector relatively forward with respect to the bolt as shown in Fig. 10, thus throwing the cartridge shell toward the right to the position B. An ejection opening 76 is provided in 30 the right wall of the casing and the shell is thus thrown out through this ejection opening.

35 Preferably the pin 74 is carried by a spring 77 secured to the left side wall of the casing. This spring mounting for the pin 74 enables the 40 pin to be withdrawn so as to avoid interference when the breech bolt and other parts are to be removed through the rear of the casing. The spring has the further advantage of providing a limited resilience which avoids excessive shock 45 incident to the ejection operation.

50 It has already been stated that with the breech bolt in its forward position as shown in Fig. 2 the extractor 69 projects into the notch 71 in the barrel. This would prevent removal of the 45 barrel and no attempt should be made to remove it with the parts in this position. Ordinarily and preferably when the tube 16 is to be moved rearward as shown in Fig. 5 preliminarily to removing the barrel, the slide 27 and the 55 piston rod 28 are in their rearward positions as shown in the same figure. In the event, however, that the slide and the piston rod are permitted to remain in their forward positions as shown in Fig. 4, a shoulder 16^c on the tube 16 engages the forward end of the slide 27, thus causing the slide to move rearward as the tube moves. This rearward movement of the slide serves to move the breech bolt 45 rearward to a sufficient extent to withdraw the extractor 69 from the 60 barrel notch 71. This prevents any injury to the extractor 69, even though the slide and bolt have not been moved to their rearward positions prior to the operations incident to the removal of the barrel.

65 70 Mounted in a hole in the breech bolt 45 is a firing pin 78 capable of limited longitudinal movement and having an enlarged head 78^a at the rear. The firing pin is provided with a lug 79 which projects upward through a suitable slot in the 75 breech bolt and when the parts are in their rearward positions, as shown in Fig. 3, the lug 79 projects into an opening 80 in the link 46. The forward edge of the opening 80 is curved and serves as a cam surface to engage the lug 75

79 and thus move the firing pin 78 relatively rearward during rearward movement of the breech bolt. The lug 79 serves to positively prevent the firing pin from coming into engagement with the cartridge except when the breech bolt is in its forward position as shown in Fig. 2.

For actuating the firing pin 78 there is provided a hammer 81 pivoted at 82 in a recess in the top plate 4. Fig. 3 shows the hammer in 10 cocked position, it being so held by a sear 83 pivoted to the plate 4 at 84 and engaging a shoulder 81^a extending transversely of the hammer. The sear 83 is biased toward its engaged position by a spring pressed plunger 85. The hammer 15 is biased toward its firing position by means of a link 86 pivoted to the hammer at 87. The link is supported and guided at the rear by a lug 88 through which it extends. A spring 89 surrounds the link and abuts against the lug 88. The forward end of the spring abuts against a shoulder 20 on the link.

The hammer is cocked by engagement with the slide 27 and its associated parts as they move rearward from the position shown in Fig. 25 to the position shown in Fig. 3. To facilitate cocking the slide 27 is provided with two upward projecting lugs 90, 90 which initially engage the hammer to start the cocking movement thereof. Subsequently the hammer is engaged by the upward extension 46^a on the link 46 which serves to 30 move it to its fully cocked position as shown in Fig. 3.

In order that the hammer, when released, may 35 actuate the firing pin there is provided an intermediate striker 91 carried by the link 47. This striker is in the form of a rod slidably mounted in a hole in the link and having longitudinal movement therein, such movement being limited by a pin 92 extending transversely of the link and extending through a notch in the rod or striker. The relationship of the parts is such that when 40 the breech bolt is in its forward position the striker 91 is in engagement with the enlarged rear end portion 78^a of the firing pin 78. When 45 the hammer is released in the manner to be presently described it moves from the position shown in Fig. 3 to the position shown in Fig. 2, engaging the striker and driving it forward to 50 actuate the firing pin and to thus cause the cartridge to be fired.

The lower right hand portion of the sear 83 is cut away to provide a notch for a sear operating lever 93. This lever is clearly shown in Fig. 2, but a part of it is omitted from Fig. 3 55 in order that the sear itself may be more clearly shown. The operating lever 93 is preferably pivoted coaxially with the hammer 81 and the forward end thereof is in engagement with the downward facing top wall of the before-mentioned notch in the sear. The tail portion 93^a of the lever is adapted to engage the top wall of the casing, as shown in Fig. 3, so as to limit movement in the clockwise direction. For actuating the lever 93 and for thus in turn actuating 60 the sear 83 there is provided an upward projection 94 at the rear of the slide 27 and at the right hand side thereof. When the parts reach their forward positions as shown in Fig. 2 the extension 94 on the slide 27 is forced underneath 65 the forward portion of the lever 93, thus forcing the said forward portion upward and moving the sear 83 in the counter-clockwise direction so as to release the hammer.

For holding the slide 27 in its rear position 70 as shown in Fig. 3 there is provided a second

sear 95 pivoted to the bottom plate 5. This sear is spring pressed upward and engages a notch 96 in the bottom of the slide. Carried by the rear plate 1 is a manually operable trigger 97 having a tail portion which projects forward through an opening in the plate and is adapted to engage the sear 95. A spring pressed plunger 98 tends to hold the trigger in its rearward inoperative position.

In initially loading the gun in order to start 10 firing it is ordinarily necessary to operate the mechanism of the gun by hand in order to withdraw the first cartridge from the belt and transfer it into the position shown in Fig. 3. For this purpose there is provided a handle 99 extending 15 through a slot 100 in the right side wall of the casing and fitting a hole 101 in the slide 27. The slot 100 is enlarged at its rear end and the handle 99 is so formed that it can be removed only when in register with the enlarged rear end 20 of the slot.

When the trigger 97 is pressed forward the sear 95 is disengaged from the slide 27 and the slide moves forward, causing the links 46 and 47 and the breech bolt 45 to assume the positions 25 shown in Fig. 2. When these positions are reached the projection 94 on the slide 27 releases the hammer 81 in the manner already described, thus actuating the firing pin and causing firing. Thereupon the gases of explosion enter the cylinder 31 and drive the piston 29 rearward, thus moving the slide 27 rearward and causing the various parts of the gun to assume the relative 30 positions shown in Fig. 3. During this rearward movement a new cartridge is extracted from the belt and the shell of the exploded cartridge is ejected in the manner already described. If, in the meantime, the trigger 97 has been released and permitted to resume its normal position, the slide is caught and held by the sear 95 and no 40 further firing takes place. If, however, the trigger 97 is held in its forward firing position the parts immediately again move forward to the firing position shown in Fig. 2 and firing again occurs. Thus volley firing may be continued so 45 long as the trigger 97 is held and so long as the supply of cartridges in the belt is not exhausted.

In addition to the parts already described the gun may also be provided with a means for retarding the rate of fire. This means may be included or omitted as desired. 50

As shown, particularly in Figs. 22, 23 and 24, there is provided an auxiliary sear 102 mounted coaxially with the sear 83 and biased toward its engaged position by a spring 103. The sear 102 55 is positioned at the left side of the gun and is adapted to engage the same shoulder 81^a in the hammer that is engaged by the sear 83. For disengaging the sear 102 from the shoulder 81^a there is provided a slide 104 at the left side of 60 the gun, this slide being guided in part by the pivot pin at 82 and in part by a pin 105 projecting inward from the left side of the recess in the top plate 4. When the slide 104 is in its rearward position as shown in Fig. 24 the sear 102 65 engages the shoulder 81^a and prevents movement of the hammer even though the sear 83 be released in the manner heretofore described. If the slide 104 be moved forward to the position shown in Fig. 23 an extension 104^a on the slide 70 engages the sear to disengage it and thus release the hammer.

Secured to the top plate 4 is a bracket 106, this bracket being U-shaped and carrying two pivot pins 106^a and 107. Mounted on the pivot 75

pin 106^a is a ratchet wheel 108 and an escape-
ment wheel 109, these two wheels being con-
nected together for movement in unison.
Mounted on the pivot pin 107 is an escapement
weight 110 having teeth thereon which engage
the teeth on the wheel 109. The teeth on the
escapement weight are so related to the teeth on
the wheel that the weight is forced to oscillate
as the wheel is turned. Thus the weight offers
resistance to the turning of the wheel.

Pivotaly mounted at 111 is a lever 112 which is
biased for movement in the counter-clockwise
direction by means of a spring 113. Pivotaly
connected at 114 to the lever 112 is a ratchet arm
115 having teeth thereon adapted to engage with
the teeth of the ratchet wheel 108. A spring 116
serves to bias the arm 115 in the clockwise direc-
tion, thus tending to hold it in engagement with
the wheel. The lever 112 is positioned at the left
20 side of the casing and is adapted to be engaged
and reset by a cam surface 117 on the slide 27.
Thus when the slide moves rearward the lever
112 is moved or reset in the clockwise direction
25 to the position shown in Fig. 2. In so moving the
teeth on the arm 115 may snap over the teeth
on the wheel 108 without causing the wheel to
rotate.

It will be seen that the lever 112 after having
been moved by the cam 117 to the position shown
30 in Fig. 2, tends to move in the counter-clockwise
direction, but it can so move only by causing cor-
responding rotation of the ratchet wheel 108.
The ratchet wheel is restrained from rapid move-
ment by reason of its connection with the escape-
35 ment wheel 109. Thus the lever 112 is permitted
to move in the counter-clockwise direction, but
only at a relatively slow rate determined by the
action of the escapement weight 110.

The lever 112 is provided with a forward ex-
40 tension 112^a which is adapted to engage the rear
edge of the slide 104. Thus as the lever moves
relatively slowly in the counter-clockwise direc-
tion, the extension 112^a engages the slide 104 so
45 that the slide is moved forward to release the
sear 102. Fig. 24 shows the extension 112^a just
coming into engagement with the slide, the slide,
however, not yet having been moved.

From the foregoing description it will be appar-
50 ent that when the main operating slide 27 moves
rearward to the position shown in Fig. 3, the lever
112 is moved in the clockwise direction to the po-
sition shown in the same figure. If the trigger 97
is maintained in its depressed position the slide
27 with its associated parts immediately moves
55 forward to the position shown in Figs. 2 and 20,
thus releasing the main sear 83 in the manner al-
ready described. Firing, however, does not im-
mediately occur for the reason that the hammer
is still held by the auxiliary sear 102. However,
60 as soon as the cam surface 117 on the slide 27
moves out of the way of the lever 112 the said
lever starts to move relatively slowly in the
counter-clockwise direction, the extension 112^a
thereof eventually engaging the slide 104 as
65 shown in Fig. 24. The slide 104 is then pushed
forward to release the sear 102 and thus permits
the hammer to move and cause firing as shown
in Fig. 21. With this retarding mechanism in use
70 otherwise would be, the amount of decrease in
the rate being in large measure dependent upon
the size of the escapement weight 110.

It will be observed that when the retarding
75 mechanism is used the main sear 83 normally has
no control of the firing, but the said sear never-

theless serves as a safety means to prevent pre-
mature release of the hammer in the event of
any jamming or malfunctioning of the gun. The
sear 83 prevents release of the hammer before the
breach bolt reaches its forward locked position.

The retarding mechanism serves not only to
decrease the rate of fire but also to increase accu-
racy. The momentary delay between the closing
of the breech and the firing of the cartridge per-
mits vibrations to expend themselves so that the
10 gun is in a static condition at the instant of fir-
ing.

In order that the retarding mechanism may be
rendered inoperative when not required, there is
preferably provided a transverse shaft or pin 118
15 adapted to be oscillated by means of a lever 119
on the exterior of the casing. Secured to the
pin 118 is a finger 120 which is adapted to engage
the lever 112, as shown in Fig. 23, to maintain it
20 in its rearward or inoperative position. Assoc-
iated with the finger 120 is a projection 121 which
engages an extension 104^b on the slide 104 to
hold the slide in its forward position and to thus
hold the sear 102 in its inoperative position, as
also shown in Fig. 23. With the parts in this po-
25 sition the retarding mechanism is entirely inop-
erative and the action of the gun is exactly the
same as it would be if the said mechanism were
not provided.

By moving the lever 119 in the counter-clock-
wise direction the finger 120 and the projection
121 can be moved to the positions shown in Fig.
24, thus freeing the retarding mechanism and
permitting it to operate in the manner which has
already been fully described.

I do not claim as a part of the present invention
the features of construction which facilitate
the removal of the barrel, such features being
particularly illustrated in Figs. 4 to 7 of the
drawings. These features constitute the subject 40
matter of my copending application for Gas op-
erated automatic firearm, Ser. No. 11,790, filed
March 19, 1935, as a division of this application.

I do not claim as a part of the present invention
the firing mechanism of the firearm as dis-
closed or the mechanism for retarding the rate
of fire, these mechanisms constituting the sub-
ject of my copending application for Firing mech-
anism for automatic firearm, Ser. No. 11,791, filed
March 19, 1935, as a division of this present ap-
plication.

What I claim is:

1. In an automatic firearm, the combination
of a barrel, a breech casing carrying the barrel
and having a transverse cartridge feed channel
therein immediately below the rear portion of
the barrel, the said feed channel being closed
at the front and having a width only slightly
greater than the length of the cartridges, a mov-
able breech bolt in the casing, an operating slide
below the feed channel automatically movable
rearward upon firing connected with the breech
bolt to move the same and having a cam path
at least a part of which is inclined with respect
to the direction of movement, a transversely and
rectilinearly movable feed slide below the feed
channel and having a width less than that of
said feed channel, means on the feed slide en-
gaging the cam path of the operating slide and
thus serving to transversely move the feed slide,
70 and means for withdrawing the cartridges rear-
ward from the feed channel and lifting them
upward into alignment with the chamber in said
barrel.

2. An automatic firearm comprising in com-

bination, a barrel, a breech casing carrying the barrel and having a transverse cartridge feed channel therein immediately below the rear portion of the barrel, a movable breech bolt in the 5 casing, an operating slide below the feed channel automatically movable rearward upon firing connected with the breech bolt to move the same, a transversely movable feed slide below the operating slide, means on the operating slide and on 10 the feed slide having cooperating elements normally serving to enable the former to operate the latter, and means for withdrawing the cartridges rearward from the feed channel and lifting them upward into alignment with the chamber in said 15 barrel.

3. An automatic firearm comprising in combination, a barrel, a breech casing carrying the barrel and having a transverse cartridge feed channel therein immediately below the rear portion 20 of the barrel, a movable breech bolt in the casing, an operating slide below the feed channel automatically movable rearward upon firing connected with the breech bolt to move the same and having at the bottom thereof a cam path 25 at least a part of which is inclined with respect to the direction of movement, a transversely movable feed slide below the operating slide, means on the feed slide at the top thereof engaging the cam path of the operating slide and 30 thus serving to transversely move the feed slide, a pawl on the feed slide partly overlying the operating slide and adapted to engage a cartridge belt in the feed channel, and means for withdrawing the cartridges rearward from the feed 35 channel and lifting them upward into alignment with the chamber in said barrel.

4. An automatic firearm comprising in combination, a barrel, a breech casing carrying the barrel and having a transverse cartridge feed 40 channel therein immediately below the rear portion of the barrel, the said feed channel being closed at the front and having a width only slightly greater than the length of the cartridges, a movable breech bolt in the casing, an operating slide below the feed channel automatically 45 movable rearward upon firing connected with the breech bolt to move the same and having at the bottom thereof a cam path at least a part of which is inclined with respect to the direction of movement, a transversely and rectilinearly 50 movable feed slide below the feed channel and having a width less than that of said feed channel, means on the feed slide engaging the cam path at the bottom of the operating slide and thus serving to transversely move the feed 55 slide, and means for withdrawing the cartridges rearward from the feed channel and lifting them upward into alignment with the chamber in said barrel.

60 5. The combination in an automatic firearm, of a barrel, a breech casing carrying the barrel and having a transverse cartridge feed channel therein below the rear portion of the barrel, a movable breech bolt in the casing, a transversely 65 movable feed slide in the casing below the feed channel, an operating slide in the casing movable rearward upon firing connected with the breech bolt to move the same, means on the operating slide and on the feed slide having cooperating elements normally serving to enable the former to operate the latter, the cooperating elements of the last said means being readily disengagable from each other while the operating and feed slides are within the breech casing to 70 thereby permit the operating slide to be removed 75

longitudinally from the casing independently of the feed slide, and means for withdrawing the cartridges rearward from the feed channel and lifting them upward into alignment with the chamber in said barrel.

6. The combination in an automatic firearm, of a barrel, a breech casing carrying the barrel and having a transverse cartridge feed channel therein immediately below the rear portion of the barrel, a movable breech bolt in the casing, 10 a transversely movable cartridge feed slide below the feed channel, an operating slide below the feed channel and above the feed slide automatically movable rearward upon firing connected with the breech bolt to move the same and having at the bottom thereof a cam path at least a part of which is inclined with respect to the direction of movement, means on the top of the feed slide normally engaging the cam path of the operating slide and thus normally serving 20 to operate the feed slide, the last said means being readily disengageable from the cam path to permit the operating slide to be removed longitudinally from the casing independently of the feed slide, and means for withdrawing the cartridges rearward from the feed channel and lifting them upward into alignment with the chamber in said barrel. 25

7. The combination in an automatic firearm, of a barrel, a breech casing carrying the barrel and having a transverse cartridge feed channel therein immediately below the rear portion of the barrel, a movable breech bolt in the casing, a transversely movable cartridge feed slide below 30 the feed channel, an operating slide automatically movable rearward upon firing connected with the breech bolt to move the same and having a cam path at least a part of which is inclined with respect to the direction of movement and which has a transversely unobstructed portion, means on the feed slide normally engaging the cam path to cause normal transverse movements of the feed slide, the last said means being readily separable transversely from the cam path when in register with the unobstructed 35 portion thereof to permit the operating slide to be removed longitudinally from the casing independently of the feed slide, and means for withdrawing the cartridges rearward from the feed 40 channel and lifting them upward into alignment 45 with the chamber in said barrel. 50

8. The combination in an automatic firearm, of a barrel, a breech casing carrying the barrel and having a transverse cartridge feed channel therein immediately below the rear portion of the barrel, a movable breech bolt in the casing, a transversely movable cartridge feed slide below the feed channel, a cam path engaging means on the feed slide, an operating slide automatically 55 movable rearward upon firing connected with the breech bolt to move the same and having a cam path which engages the said means on the feed slide and at least a part of which is inclined with respect to the direction of movement of the operating slide so as to cause normal transverse movements of the feed slide, the said cam path serving when the operating slide is within its normal range of movement to retain engagement with the engaging means on the bottom of the feed 60 slide and the said cam path being transversely unobstructed at one end to permit disengagement of the said means therefrom when the operating slide is in an abnormal position, and means for withdrawing the cartridges rearward from the 65 slide and the said cam path being transversely unobstructed at one end to permit disengagement of the said means therefrom when the operating slide is in an abnormal position, and means for 70 withdrawing the cartridges rearward from the 75

feed channel and lifting them upward into alignment with the chamber in said barrel.

9. An automatic firearm comprising in combination, a barrel, a breech casing carrying the barrel and having a transverse cartridge feed channel and an unobstructed transverse feed slide guide channel therein below the rear portion of the barrel, a movable breech bolt in the casing, a feed slide below the feed channel transversely movable in said feed slide guide channel, an operating slide automatically movable rearward upon firing connected with the breech bolt to move the same, means on the operating slide and on the feed slide having cooperating elements normally serving to enable the former to operate the latter, the cooperating elements of the last said means being readily disengageable from each other to permit the feed slide to be transversely removed from the casing, and means for withdrawing the cartridges rearward from the feed channel and lifting them upward into alignment with the chamber in said barrel.

10. An automatic firearm comprising in combination, a barrel, a breech casing carrying the barrel and having a transverse cartridge feed channel and an unobstructed transverse feed slide guide channel therein immediately below the rear portion of the barrel, a movable breech bolt in the casing, a cartridge feed slide below the feed channel transversely movable in said feed slide guide channel and removable transversely from the casing, an operating slide below the feed channel and above the feed slide automatically movable rearward upon firing connected with the breech bolt to move the same and having at the bottom thereof a cam path at least a part of which is inclined with respect to the direction of movement, means on the top of the feed slide normally engaging the cam path of the operating slide and thus normally serving to operate the feed slide and to prevent transverse removal thereof from the casing, the last said means being readily disengageable from the cam path to permit the feed slide to be transversely removed from the casing, and means for withdrawing the cartridges rearward from the feed channel and lifting them upward into alignment with the chamber in said barrel.

11. An automatic firearm comprising in combination, a barrel, a breech casing carrying the barrel and having a transverse cartridge feed channel therein immediately below the rear portion of the barrel, a movable breech bolt in the casing, a transversely movable cartridge feed slide below the feed channel and removable transversely from the casing, a cam path engaging means on the feed slide, an operating slide automatically movable rearward upon firing connect-

ed with the breech bolt to move the same and having a cam path which engages the said means on the feed slide and at least a part of which is inclined with respect to the direction of movement of the operating slide so as to cause normal transverse movements of the feed slide, the said cam path serving when the operating slide is within its normal range of movement to prevent transverse removal of the feed slide from the casing and the said cam path being transversely unobstructed at one end to permit such removal when the operating slide is in an abnormal position, and means for withdrawing the cartridges rearward from the feed channel and lifting them upward into alignment with the chamber in said barrel.

12. The combination in an automatic firearm, of a barrel, a breech casing carrying the barrel and having a transverse cartridge feed channel therein, a movable breech bolt in the casing, a transversely movable cartridge feed slide adjacent the feed channel and removable transversely from the casing, an operating slide automatically movable rearward upon firing connected with the breech bolt to move the same and having a cam path at least a part of which is inclined with respect to the direction of movement, means on the feed slide normally engaging the cam path of the operating slide and thus normally serving to operate the feed slide and to prevent transverse removal from the casing, the last said means being readily disengageable from the cam path to permit the feed slide to be transversely removed from the casing, a spring means for resisting removal of the feed slide but adapted to permit such removal when pressure is applied, and means for withdrawing the cartridges rearward from the feed channel and lifting them upward into alignment with the chamber in said barrel.

13. In an automatic firearm, the combination of a barrel, a breech casing carrying the barrel and having a transverse cartridge feed channel therein below the level of the barrel, a breech bolt in the casing automatically movable rearward upon firing, an extractor movable with the bolt and serving during movements thereof to extract successive cartridges from the feed channel and to move each of them upward into alignment with the bore of the barrel, cam mechanism on the casing for causing upward and downward movements of the extractor, and a spring pressed lever carried by the breech bolt and engaging the extractor when in the extreme forward position to bias it upward into firm engagement with a cartridge.

MARRINER A. BROWNING.
